UNITED STATES PATENT OFFICE.

JOHN PAUL NICHOLAS WOOD, OF DUNDEE, FLORIDA.

ORCHARD HEATER.

Original application filed October 21, 1924, Serial No. 744,924. Divided and this application filed April 19, 1926. Serial No. 103,003.

Division of application Serial No. 744,924, filed October 21, 1924.

The object of the invention is to provide a heater of a form designed to most effectively radiate the heat of a given quantity of fuel, so that the maximum effect may be obtained, as in the heating of orchards and the like to protect trees from frosts and chilling blasts; and to provide a heater readily constructible from plastic material in order that it may be built at the point of use and constitute a comparatively small loss in the event of breakage.

With this object in view, the invention consists in a construction and combination of parts of which a preferred embodiment is illustrated in the accompanying drawings, wherein:

Figure 1 is a side elevational view of the heater, partly in section.

Figure 2 is a top plan view.

Figure 3 is a vertical sectional view on the plane indicated by the line 3—3 of Figure 1.

Figure 4 is a side elevational view, partly broken away, of the cover.

The fire-pot 1, which is adapted either for casting in Portland cement, clay or like moldable material, is of inverted frusto-conical form and provided at its upper or larger end with the handle elements 2 consisting of angular metal pieces of which one arm is embedded in the material of the heater in the casting of the latter. Preferably two handles are provided at diametrically opposite sides but in order that the heater may readily seat in an upright position, the feet 3 are provided. There are preferably three of these and they are likewise formed of angular metal pieces of which one arm of each is embedded in the material of the heater.

Intermediate between the feet 3, draft openings 4 are provided below the plane of a preferably cast iron grate 5 frictionally bearing on the interior slanting wall of the heater and being of a diameter sufficient to space it above the plane of the feet 3 and thus provide an air chamber below the grate

into which air is admitted through the lateral openings 4. Openings 6 are provided in the side wall and extend a substantial distance in the direction of the height of the heater.

In the use of the heater, the fuel is deposited in the latter on top of the grate 5 and, having been properly ignited, is kept burning by air entering through the perforations or openings in the grate and through the slotted openings 6 in the side wall, and the heater being of frusto-conical form, the lateral distribution of the heat of the fuel is more readily effected than were the heater of cylindrical formation. Also, the conical form provides for a more even draft, making for the slower consumption of fuel. Made in cement or fire clay, it is practically indestructible and will withstand the elements indefinitely, but should it be broken, it is susceptible of quick reproduction in a properly constituted mold.

When not in use, it is designed to cover the heater at the top and to this end a sheet metal cover 7 is provided, the same having a depending peripheral flange 8 in which, at diametrically opposite points, the bayonet slots 9 are formed, these slots engaging the handles and serving, together with them, as a means for interlocking the cover in place so that it may not be blown off during wind storms and may thus protect the fuel from dampness when the heater is not in use. The handles constitute means for transporting the heater from place to place.

The invention having been described, what is claimed as new and useful is:

An orchard heater consisting of a fire pot, and handle members of angular form having one arm embedded in the wall of the fire pot and the other arm extending radially from the fire pot, and a flanged cover provided with bayonet slots having detachable interlocking engagement with the handle members.

In testimony whereof he affixes his signature.

JOHN PAUL NICHOLAS WOOD.
